CRIBBAGE BOARD

Charles Scott, 2144-A W. Sono Ave., Anaheim, Calif.

Filed July 7, 1964, Ser. No. 80,734

Term of patent 7 years

(Cl. D34—5)

FIG. 1.

FIG. 2.

FIG. 3.

FIG. 4.

FIG. 5.

FIG. 1 is a top plan view of a cribbage board showing my new design;

FIG. 2 is a side elevation thereof;

FIG. 3 is a bottom plan view thereof;

FIG. 4 is a section taken along the line 4-4 of FIG. 1; and

FIG. 5 is a section taken along the line 5-5 of FIG. 1.

I claim:

The ornamental design for a cribbage board, substantially as shown.
